UNITED STATES PATENT OFFICE.

FRED H. JONES, OF CHICAGO, ILLINOIS, ASSIGNOR TO R. R. STREET & CO., OF CHICAGO,
ILLINOIS, A CORPORATION OF ILLINOIS.

SECTIONAL STOCK RACK.

Application filed April 28, 1922. Serial No. 557,217.

My invention relates to sectional stock racks and has to do more particularly with racks of the above character adapted for use in shops for storing metal bars, patterns, etc. One of the objects of my invention is the production of a sectional stock rack construction whereby from a comparatively small number of interchangeable standard parts various types of racks may be readily assembled, such as racks which may be set out in the middle of the floor, or along-side of a wall and secured thereto, or extended from the floor to the ceiling, or placed adjacent lathe or screw machines and adapted to act as a support for parts which are being machined. There are other objects of my invention and these will be more particularly pointed out in the ensuing specification and appended claims.

For a better understanding of my invention reference is to be had to the accompanying drawings, in which—

Fig. 1 is a side elevation of one form of assembled rack partly in section to show interior construction;

Fig. 2 is a double angular arm holding section;

Fig. 3 is a double straight arm holding section;

Fig. 4 is a single angular arm holding section;

Fig. 5 is a single straight arm holding section;

Figs. 6 and 7 show two different lengths of spacers;

Fig. 8 shows a clamping cap;

Fig. 9 is a ceiling supported pattern rack;

Fig. 10 is a lathe or screw machine type of support and stock rack;

Fig. 11 shows a collar for use in the head of the lathe cap;

Fig. 12 is an enlarged view of the head of the lathe rack showing the method of locking the same in its adjusted position;

Fig. 13 shows a single storage rack;

Fig. 14 shows a wall storage rack; and

Fig. 15 is a cross sectional view through a carrying section B and the tubular standard showing the rectangular construction thereof.

Referring now more in detail to the rack shown in Fig. 1, it comprises a base A preferably having four supporting legs 15. The center hub 16 is cored out so as to receive a tubular standard 17 which drops

down into the cored socket of the hub and extends upwardly to accommodate the desired number of arm holding brackets. This tubular standard 17 is preferably squared so that it will not rotate in its 60 socket. The arm receiving brackets B are also cored out and have openings therethrough to slide over the standard 17 so that they will be held against rotation thereon. Thus, the brackets B may be dropped 65 down over the standard in various positions and are maintained against rotation thereon. The bracket B is provided with oppositely extending bosses 18 set at an angle and adapted to receive rack arms 19 which 70 are preferably made of square steel tubing the same as the standard 17 and are removably inserted in the sockets of the brackets.

In a rack of the type shown in Fig. 1 I 75 preferably provide arms 19 of gradually receding length as indicated in the drawing so that the stock may be more readily handled. A suitable cap C is placed over the top end of the standard 17 so that the 80 assembled parts may be more firmly clamped together. To this end a rod 20 is passed through the tubular standard 17 and threaded into a nut 21 non-rotatably held in a socket 22 cast in the under side of the 85 base A. A second nut 23 is then threaded onto the top end of the clamping rod and drawn up until the parts are all firmly clamped.

The rack may then be used in various 90 ways and by setting the sections along the floor may be arranged to carry bars of material horizontally across the arms 19.

The rack may be built up in various other ways by using other sections as D, E or F, 95 and also spacing them apart when necessary by using different sized spacers as G and H. Thus, innumerable combinations and arrangements may be readily supplied by the interchangeability of the parts. 100

In Fig. 9 I have shown another type of rack adapted to be extended to the ceiling and secured thereto by the ceiling bracket J. This bracket is cored out the same as the others and adapted to slide down over the 105 tubular standard 17 and suitably secured to the ceiling such as by lag screws. In the rack shown in Fig. 9 straight cross arm sections or brackets D are used carrying the straight tubular arms 29 which are slidably 110

inserted in the sockets of the brackets D. These tubes 29 are also preferably squared although other shapes may be used if desired. Spacers G are shown between the sections D 5 thus spacing the arms 29 apart a suitable distance to carry patterns, such as for gears, wheels and the like. It is not necessary that the rack be built up to the top of the standard 17 as in Fig. 1 and in order to securely 10 hold the sections D and G in place I provide a collar K which is slipped down over the tube 17 and held in place by set screw 30.

In Fig. 10 I have shown another form of rack, being a single arm lathe or screw 15 machine type adapted to be set in alignment with the head stock of the machine and not only carry the bar material to be machined but also arranged to support the bar being worked on. In this type of rack I have 20 shown a base L of the three leg type as the rack is equipped with the single arm brackets. In building up the rack I insert the usual square tubular standard 17 into a socket in the base L and slip the brackets F 25 down over the tube. In the present case instead of using a cap C I provide a bar support M adjustably held in the tube 17. The support M consists of a lower fixed part 32 and an upper pivotally connected part 33, the two parts being clamped together by 30 the swinging nut 34, in the usual manner. The shank 35 of the support M may be inserted in the top of the tubular standard 17 and a bolt 37 is threaded through the 35 collar surrounding the tube 17 and then through the tube to engage the shank 35 so as to lock it in the tube in alignment with the spindle of the machine. In using the support with very small stock a restricting 40 collar such as is shown in Fig. 11 may be used in the support M.

It will also be apparent that the type of rack shown in Fig. 10 may be used to set 45 up against walls on account of the corner type of base L which is used. In such cases, however, the support M may be replaced by a cap C.

In Fig. 13 I have shown another form of 50 rack being of the single storage type, using bases L and single straight arm brackets F, suitably spaced apart by means of spacers H. Square tubular supports 39 are inserted 55 into the sockets and the parts held together by the cap and clamping rods.

In Fig. 14 I have shown a wall storage 55 type of rack using the base L and brackets F together with the ceiling bracket J. Wall brackets N are provided having sockets to receive the bars 39, which sockets are merely open topped so-called saddle members 40, 60 flush with the top of the bar 39.

For the purpose of illustrating my invention I have shown several preferred rack arrangements and preferred interchangeable parts, but it is to be understood that I contemplate using it in other ways than that shown and described, and therefore, do not desire to be limited to these arrangements but aim to cover all that which comes within the spirit and scope of the appended claims. 70

What I claim as new and desire to secure by United States Letters Patent is:—

1. In an interchangeable sectional stock 75 rack construction, a base provided with a vertical socket, a tubular standard for insertion in the base socket, interchangeable of arm holding sections having horizontally extending socketed bosses and spacer sections having vertical openings therethrough for receiving the standard readily removable tubular supporting arms in said section sockets, said sections being placed over the standard with adjacent ones engaging each other by direct contact to build up the rack, and suitable locking means to hold the assembled parts, whereby racks of different heights may be readily constructed. 80

2. A sectional stock rack for holding 85 metal bars and the like comprising a cast metal base having a central vertically socketed hub and supporting feet, an angular tube nonrotatively set into the socket in the base, a plurality of cast metal arm holding sections nonrotatively and removably fitting 90 over the tube and having laterally extending bosses with rectangular sockets therein, said sections engaging each other in building up the rack so as to themselves extend throughout the length of the tube, rectangular metallic tubular stock holding arms 95 removably inserted in said latter sockets, and means for holding the sections and base securely upon the tube including a rod extending through the tube with fastening 100 means upon its opposite ends. 105

In witness whereof, I hereunto subscribe my name this 3rd day of March A. D., 1922.

FRED H. JONES.
